卷之三

INVENTOR:

Peter Linder

BY

Miller, Strom & Co. ATTORNEYS.

UNITED STATES PATENT OFFICE.

PETER LINDER, OF CHICAGO, ILLINOIS.

CONVERTIBLE FURNITURE.

1,384,327.

Specification of Letters Patent. Patented July 12, 1921.

Application filed September 24, 1920. Serial No. 412,515.

To all whom it may concern:

Be it known that I, PETER LINDER, a citizen of the United States, residing at Chicago, in the county of Cook and State of Illinois, have invented new and useful Improvements in Convertible Furniture, of which the following is a specification.

This invention has for its object to provide a couch which is so constructed that it may be converted into a chair having a table in front of the same.

The object stated is attained by means of a novel combination and arrangement of parts to be hereinafter described and claimed, and in order that the same may be better understood, reference is had to the accompanying drawings, forming a part of this specification.

In the drawings—

20 Figure 1 is a perspective view of the couch;

Fig. 2 is an enlarged longitudinal section thereof;

25 Fig. 3 is a longitudinal section showing the structure converted into a combined chair and table;

Fig. 4 is a cross section on the line 4—4 of Fig. 2, and

30 Fig. 5 is a cross section on the line 5—5 of Fig. 3.

Referring specifically to the drawings, the top of the couch comprises a main body portion 10 and a head portion 11, these two portions or sections being separate and suitably upholstered.

35 The frame of the couch consists of a base 12 having upstanding side walls 13 at its foot end and similar walls 14 at its head end. The section 10 of the couch top has 40 depending walls 15 extending throughout substantially one half the length thereof from the foot end, and adjacent to the latter end the walls 15 are connected by a cross rod 16 which seats in vertical slots 18, in 45 the walls 13, opening through the top of the latter. The rod 16, when seated in the slots 18 serves as the pivot of the section 10 to permit the same to be swung to upstanding or vertical position, as shown in Fig. 3, in 50 which position it serves as the back of a chair as will be presently described.

The walls 15 are on the outside of the walls 13, and at the foot end the latter are connected by a cross piece 19 for lending a 55 finished appearance to this end of the couch. In advance of the cross piece 19, the walls

13 are spanned by a cross brace 20. The rod 16 lies between the parts 19 and 20.

The rod 16 seats removably in the slots 18, and thence the section 10 is detachable 60 from the base 12.

To the head end of the base 12 is hinged a frame which supports the section 11, and is adjustable to function as a table. This frame consists of an upstanding head wall 65 21 carried by side walls 22 connected intermediate their ends by a transverse wall 23 and a bottom wall 24. This structure defines a compartment the end walls of which are composed of the walls 21 and 23, whereas 70 the bottom of the compartment is the wall 24, and the sides are the portions of the walls 22 which extend between the walls 21 and 23. This compartment serves as a convenient place for storing bedding, etc. 75

The walls 22, between the walls 21 and 23 are inclined at the top to support the section 11, the latter having cleats 24^a at its side edges which define slots in which the top edges of the walls 22 seat. The section 80 11 seats removably on the top edges of the walls 22 so that it may be taken off when the couch is to be converted into a chair in the manner to be presently described.

The hereinbefore head frame which carries the section 11 has its side walls 22, beyond the wall 23, connected by a rod 25 which is journaled in the walls 14 and thus provides a pivotal support for the head frame, so that the latter may be swung from 90 horizontal to vertical position to serve as a table, as shown in Fig. 3. When the head frame is swung to vertical position, the wall 21 assumes a horizontal position and it now serves as a table top, the sides of the table 95 being the walls 22, and the wall 23 serving as a shelf located beneath the table top. The table is closed up at the back by the wall 24 which is suitably paneled or otherwise finished to lend an attractive appearance to the structure. 100

Back of the cross rod 25, the side walls 14 are connected by a cross piece 26 to obtain a finished appearance of this end of the couch base when the head frame is swung 105 up to obtain the table structure hereinbefore described.

The cross rod 25 seats in apertures 27 in the walls 14 and from said apertures lead slots 28 which open through the ends of 110 said walls, the purpose of these slots being to permit removal of the rod and thus effect

the separation of the head frame from the main body of the couch, thereby facilitating moving the couch and also enabling the same to be reduced in compass for convenience in transportation and storage. The section 10 is removable for the same purpose.

Above the cross piece 26 is a removable cross strip 29 forming a continuation thereof and having side pieces 30 to fit inside the walls 14 over the slots 28, said side pieces being detachably fastened by screws 31. Above the cross strip 29 is a curved cross piece 32.

In order to hold the head frame in upright position when it is being used as a table, the side walls 22 carry resilient latch hooks 33 which engage keeper notches 34 in the inner faces of the walls 14, and the walls 22 also have stop lugs 35 on their outer faces which seat on the top edges of the walls 14.

When the structure is used as a couch the walls 14 and 15 are in alinement and form the sides of the couch, these walls being made ornamental as the fancy may dictate, especially around the exposed ends of the pivot rods 16 and 25. That portion of the section 10 which extends beyond the walls 15 rests on the top edges of the walls 14 not occupied by the section 11 so that said section 10 is firmly supported.

Sagging of the section 10 intermediate its ends is prevented by positioning beneath the same, and between the walls 13, a box-like structure 36 having a hinged lid 37 which is upholstered. This structure is removable so that it may serve as a seat when the section 10 is swung up to function as the back of a chair. When the section 10 is in the last-mentioned position the device 36 is placed between the walls 15 and on top of the walls 13, with the upholstered lid 37 uppermost, so that it now functions as the seat of a chair, the back of the latter being the part 10, and the sides or arm rests being the walls 15.

The walls 13 have inturned strips 38 at the top engageable by retaining and guide strips 39 on the bottom of the seat structure for holding the same in place. The box-like structure of the seat provides a convenient receptacle for the storage of bedding, etc.

Upward displacement of the section 11 is prevented by having one of the cleats 24^a on each side extending far enough so that one end may seat under a cross rail 40 connecting the wall 22 along the wall 21, and the other end in a notch 41 in the wall 23. By a sliding and tilting movement, the projecting ends of the cleats can be disengaged from the parts 40 and 41, after which the section 11 can be lifted and removed.

The couch will be provided with casters

42 so that it may be readily moved about. The casters of the head portion which is convertible into a table are carried by a hinged support 43 which can be folded in out of the way as shown in Fig. 3 when the table construction is had.

In the drawings, Figs. 1 and 2 show the article arranged as a couch, whereas Fig. 3 shows the same converted into a chair with a table in front thereof, the section 10 having been swung as described to form the chair back, and the head section having been swung to form the table.

I claim:

1. A couch comprising a top consisting of 80 a main body section and a separate head section, the main body section having depending side walls, a base frame to which said side walls are pivotally connected to permit the main body section to be swung to 85 upright position and serve as a chair back, the side walls forming arm rests, a seat adapted to be associated with said chair back and the arm rests, and detachable and 90 separate therefrom, and a frame on which the aforesaid head section is detachably supported, said frame being pivotally connected to the head end of the base frame and having side pieces forming extensions of the aforesaid side walls, said frame also 95 having an upstanding end wall and being adjustable to place said end wall in horizontal position to serve as a table top.

2. A couch comprising a top consisting of 100 a main body section and a separate head section, the main body section having depending side walls, a base frame to which said side walls are pivotally connected to permit the main body section to be swung to 105 upright position and serve as a chair back, the side walls forming arm rests, a seat adapted to be associated with said chair back and the arm rests, and detachable and 110 separate therefrom, a frame on which the aforesaid head section is detachably supported, said frame being pivotally connected to the head end of the base frame and having side pieces forming extensions of the aforesaid side walls, said frame also 115 having an upstanding end wall and being adjustable to place said end wall in horizontal position to serve as a table top, and a transverse wall between the side pieces of the frame inside the end wall.

3. A couch comprising a top consisting of 120 a main body section and a separate head section, the main body section having depending side walls, a base frame to which said side walls are pivotally connected to permit the main body section to be swung to 125 upright position and serve as a chair back, the side walls forming arm rests, a seat adapted to be associated with said chair back and the arm rests, and detachable and 130 separate therefrom, a frame on which the

aforesaid head section is detachably supported, said frame being pivotally connected to the head end of the base frame and having side pieces forming extensions of the aforesaid side walls, said frame also having an upstanding end wall and being adjustable to place said end wall in horizontal position to serve as a table top, a transverse wall between the side pieces of the frame inside the end wall, and a bottom wall between the side pieces, and the end and transverse walls.

4. A couch comprising a top consisting of a main body portion and a separate head portion, said main body portion having depending side walls, a base frame to which said side walls are pivotally connected to permit the main body portion to be swung to upright position and serve as a chair back, the side walls forming arm rests, and a seat adapted to be associated with said back and arm rests, and detachable and separate therefrom.

5. A couch comprising a top consisting of a main body portion and a separate head portion, said main body portion having depending side walls, a base frame to which said side walls are pivotally connected to

permit the main body portion to be swung to upright position and serve as a chair back, the side walls forming arm rests, and a seat adapted to be associated with said back and arm rests, and detachable and separate therefrom, said seat being removably supported by the base frame.

6. A couch comprising a top consisting of a main body portion and a separate head portion, said main body portion having depending side walls, a base frame consisting of a bottom and upstanding side walls at the respective ends thereof, a support for the aforesaid head section connected to the base side walls at one end thereof, the main body portion of the top being pivotally connected to the base side walls at the other end of the base, and the depending side walls of the main body portion of the top being arranged to form continuations of the last mentioned base side walls, and said main body portion of the top being adapted to be swung to upright position to serve as a chair back, and a seat adapted to be associated with said back and detachable and separate therefrom.

In testimony whereof I affix my signature. 55
PETER LINDEM
